UNITED STATES PATENT OFFICE.

ALFRED WALKER, OF HUYTON, ENGLAND.

HOLDER OR CARRIER FOR TOILET-PAPER ROLLS.

1,070,641.

Specification of Letters Patent. Patented Aug. 19, 1913.

Application filed September 19, 1912. Serial No. 721,245.

To all whom it may concern:

Be it known that I, ALFRED WALKER, a subject of the King of England, residing at Park House, Huyton, in the county of Lancaster, England, have invented a certain new and useful Improved Holder or Carrier for Toilet-Paper Rolls or Like Articles, of which the following is a specification.

This invention relates to an appliance mainly for use as a holder or carrier for toilet-paper rolls as customarily used in lavatories, but which is also applicable as a holder for sewing-cotton reels and like articles.

A holder or carrier according to my invention is constructed in the following manner:—A length of wire rod of suitable gage is first bent into $\cap$ shape or configuration, and then each limb so formed is bent into U shape, a more or less rectangular frame being thus constructed. Spanning the rear longitudinal members of the frame, being clipped thereto (but not tightly) and preferably adjustable longitudinally thereon are one or more bridge or distance pieces provided with slots or holes by the aid of which the appliance may be attached to a wall or other convenient support.

I will further describe my invention with the assistance of the accompanying sheet of explanatory drawings, in which:—

Figure 1 is a front elevation of an appliance, more particularly for use as a toilet-paper roll carrier. Fig. 2 is a plan view; and Fig. 3 is a side view, partly in section.

As illustrated, a length of wire rod is bent into $\cap$ shape and then each limb so formed is bent into U shape: the free or outer extremities of the front members a of the frame,—which preferably extend as shown to positions approximately in alinement with the transverse portion b —are formed into small loops a^1 which prevent accidental displacement of the paper roll.

Spanning the rear members d of the

frame, being clipped thereto,—but not tightly in order to permit of said members being twisted somewhat—and adjustable longitudinally thereon, are two sheet metal bridge plates e provided with slots f , by means of which and screws g the device may be attached to a foundation board or plate h , or other convenient support: said bridge plates e also maintain the rear members d apart.

In applying the roll c , limbs a are first deflected toward each other by the fingers and the roll is passed or threaded over same: said spring limbs are then released, and by bearing against the paper wall prevent the roll from revolving until the free end of the paper is pulled more or less vigorously.

It will be obvious that the size and proportions of the device will vary according to the use intended.

Having now described my invention, what I claim as new and desire to secure by Letters Patent is:—

A device for holding or carrying toilet paper rolls, sewing-cotton reels, and like articles, comprising a frame which has been formed by first bending a length of wire rod into $\cap$ shape, and then bending each limb or member so formed into U shape; and one or more—preferably adjustable—bridge or distance pieces spanning the rear limbs or members of said frame, which bridge or distance piece or pieces, while permitting the rear limbs or members of the frame to be twisted somewhat when the front limbs or members are deflected, maintain said rear limbs or members apart, and also constitute means whereby the device may be secured to a foundation board, wall, or the like.

In testimony whereof I affix my signature in presence of two witnesses.

ALFRED WALKER.
